DESIGN FOR A TEXTILE FABRIC OR SIMILAR ARTICLE

Jean M. Langenieux, Mount Vernon, N. Y.

Application May 21, 1941, Serial No. 101,037

Term of patent 3½ years

To all whom it may concern:

Be it known that I, Jean M. Langenieux, a citizen of the United States, residing in Mount Vernon, county of Westchester, and State of New York, have invented a new, original, and ornamental Design for a Textile Fabric or Similar Article, of which the following is a specification, reference being had to the accompanying drawing, forming part thereof.

The figure of the drawing is a plan view of a textile fabric showing my new design.

I claim:

The ornamental design for a textile fabric or similar article, as shown.

JEAN M. LANGENIEUX.
